UNITED STATES PATENT OFFICE

RALPH E. PAGE, OF BINGHAMTON, NEW YORK, ASSIGNOR TO THE TABULATING MACHINE COMPANY, OF ENDICOTT, NEW YORK, A CORPORATION OF NEW JERSEY

PUNCH DIE

Application filed June 7, 1930. Serial No. 459,782.

This invention relates to a punch die and more particularly to a die for receiving punches of rectangular cross-section. The invention is applicable to record perforating machines of the type shown in co-pending application Serial No. 450,130, filed May 6, 1930.

In the tabulating machine art it has been the practice to punch so-called tabulating cards or sheets which usually, for convenience in reading, are provided with a number of index point designations on the face thereof disposed in columnar arrangement. Gang punching machines are also provided in which a plurality of punches are disposed to cooperate with all the index point positions of the cards to record information thereon in the various columns simultaneously. Where circular holes are employed the construction of the punch die is a comparatively simple process. The employment of rectangular punches involves the provision of a die having similarly shaped openings which where a single plate is used, is costly to manufacture.

It is therefore one object of the invention to provide a punch die, of built-up construction which is low in cost and easily constructed.

Another object is to provide a punch die having rectangular openings formed by cutting cross-slots in a die block.

Further and other objects and advantages will be hereinafter set forth in the accompanying specification and claims, and shown in the drawings, which by way of illustration show what is now considered to be the preferred embodiment of the invention.

Fig. 1 is an isometric view of a portion of a punch die showing the arrangement of the openings.

Fig. 2 is a section of the die before operations are commenced upon it.

Fig. 3 is a section of the die after a slot has been cut therein.

Fig. 4 is a section of the die after a second slotting operation.

Fig. 5 is a section of the die after a cross-slotting operation.

Fig. 6 is a detail section of a filing operation.

Fig. 7 is a transverse section showing a spacing bar in position.

The die block 10 is first slotted as in Fig. 3 by a circular cutter 11 into a series of parallel slots 12 extending through the block and terminating as shown. A second cutter 13, having a wider face than cutter 11 is next employed to widen slots 12 to substantially half the depth of the block.

A series of slots 14 is then cut transversely to slots 12 as shown in Figs. 5 and 6. If desired, the angle 15 formed by the two cutters may be filed away as in Fig. 6.

A plurality of spacer bars 16 are then fitted into the transverse slots 14 and held therein by reason of a close fit or if desired, they may be prick-punched near their ends to hold them in position. The bars 16 have depending tabs 17 projecting within slots 12, forming thereby rectangular openings extending to the depth of the tabs 17. The effect of widening slot 12 by cutter 13 is to relieve the rectangular opening so that as the punch cuts a chip from the card or other material and forces it to the depth of tab 17, it will fall freely through the widened slot and not interfere with subsequent chips or punchings.

It is obvious however that the operation of widening slot 12 may be dispensed with if the punch enters to the depth of block 10 and the formation of the die then resolves itself into the cutting of slots 12, and transverse slots 14 and the insertion of spacer bars 16.

While I have shown and described and pointed out the fundamental novel features of the invention as applied to a single modification, it will be understood that various omissions and substitutions and changes in the form and details of the device illustrated and in its operation may be made by those skilled in the art without departing from the spirit of the invention. I intend to be limited therefore by the scope of the following claims.

1. A punch die consisting of a block having a series of parallel slots and a series of parallel bars positioned transversely to

said slots to form rectangular openings in said block.

5 2. A punch die consisting of a block having a series of parallel slots extending through said block and a series of transverse slots, intersecting said parallel slots and bars adapted to be seated within said transverse slots to form rectangular openings in the block.

10 3. A punch die consisting of a block having a series of parallel slots extending entirely through the material forming said block, and a series of transversely arranged parallel slots extending partially through the 15 material forming the block, and bars seated within said transverse slots to form rectangular openings in the block.

20 4. A punch die consisting of a block having a series of parallel slots extending partly through the material of the block and coinciding with a series of slots of different width extending through the remaining material of the block, a series of transverse slots, and bars seated in said transverse slots to 25 form rectangular openings in the block.

25 5. A punch die consisting of a block having a series of parallel slots extending partly through the material of the block, a second series of slots of different width coinciding with said first named series of slots, and a series of bars extending transversely to said slots, said bars having projections extending transversely into one of said series of slots to form rectangular openings in 35 the block.

35 6. A punch die consisting of a block having a series of parallel, stepped slots extending entirely through the material of the block, a series of transverse slots extending partly 40 through the material of the block and intersecting said first named slots, a plurality of bars seated within said transverse slots and having projections extending into said first named slots to cooperate with the sides thereof to form rectangular openings in the block.

In testimony whereof I hereto affix my signature.

RALPH E. PAGE.
